US00D551327S

(12) **United States Design Patent** (10) **Patent No.:** **US D551,327 S**
Lamanna (45) **Date of Patent:** **** Sep. 18, 2007**

(54) **HEATER ASSEMBLY AND HEATER ELEMENT THEREFOR**

(75) Inventor: **Dominic Lamanna**, Werribee (AU)

(73) Assignee: **Pacific Trends International Pty Ltd**, Victoria (AU)

(**) Term: **14 Years**

(21) Appl. No.: **29/264,066**

(22) Filed: **Aug. 3, 2006**

(30) **Foreign Application Priority Data**

Feb. 3, 2006 (AU) 10394/2006

(51) **LOC (8) Cl.** **23-03**

(52) **U.S. Cl.** **D23/314; D23/328**

(58) **Field of Classification Search** ..... D3/378, D3/370, 332, 339, 330, 381, 314, 354, 351, D3/386, 333, 328, 353, 361, 385, 340, 317, D3/323, 417, 357, 335, 318; 392/365, 367, 392/424, 383, 411; 415/53.1-53.3; 416/244 R, 416/247 R; 219/455.12, 455.11, 218, 424, 219/711, 130.21, 411, 553; 159/DIG. 6; 237/6, 9 R, 12.8, 67, 68; 126/237, 524, 257, 126/260, 91 A, 92 B; 165/77; 431/431; 285/283; D23/314

(57) **CLAIM**

The ornamental design for a heater assembly and heater element therefor, as shown and described.

DESCRIPTION

FIG. 1 is top perspective view of my heater assembly and heater element therefor;

FIG. 2 is a bottom perspective view of my heater assembly and heater element therefor of FIG. 1;

FIG. 3 is a bottom plan view of my heater assembly and heater element therefor of FIG. 1;

FIG. 4 is a perspective view of a portion of my heater assembly and heater element therefor of FIG. 1;

FIG. 5 is a perspective view of a portion of my heater assembly and heater element therefor of FIG. 1; and,

FIG. 6 is a further partial bottom view of a portion of my heater assembly of FIG. 1.

The broken lines which define the bounds of the claimed design form no part thereof.
